(57) **CLAIM**

The ornamental design for a stealth weathervane, as shown.

DESCRIPTION

FIG. #1. A perspective view of the weathervane from the left front angle and the attached tube upon which the weather-vane rotates after being mounted on a suitable mast or vertical shaft.

FIG. #2. A flat perspective of the right side of the weather-vane and also shows the vertical tube and its point of attachment. This figure mirrors the left side exactly.

FIG. #3. A perspective view of the weathervane from the front and slightly elevated angle.

FIG. #4. A perspective view of the weathervane from the rear and slightly elevated angle.

FIG. #5. A flat perspective of the top of the weathervane; and,

FIG. #6. A flat perspective of the bottom of the weathervane.
